WHEEL OF VARIABLE DIAMETER

Emile Henri Aubert, Romette, France; vested in
the Attorney General of the United StatesApplication November 9, 1942, Serial No. 465,945
In France July 17, 1941

11 Claims. (Cl. 74—244)

1

The present invention relates to a change speed device, including a wheel or pinion of variable diameter, said device being applicable to chain, belt or cable transmissions and comprising in particular the following features:

The wheel of variable diameter is composed of movable independent elements capable of assuming successive concentric positions, all these elements being, for each position, on one and the same circle. The passage from one position, corresponding to a circle of given diameter, to another position, corresponding to a circle of greater or smaller diameter, is produced by the spacing apart or the moving together of at least two of the movable elements.

In the case of a chain transmission having a definite pitch, the movable elements each carry teeth and they are arranged in such a manner that, when they are in the position corresponding to the circle of minimum diameter, they are all in contact with each other and form a continuous pinion in which the space separating each of the teeth is equal to the pitch of the chain.

According to another feature, the movable elements can be held stationary in a certain number of definite positions corresponding to circles, the lengths of the circumferences of said circles being equal to a whole number of pitches. The passage from one circle to the circle immediately larger or smaller is produced by the spacing apart or the moving together of at least two of the movable elements a distance equal to the difference in the circumference of the two circles, said movable elements then forming a discontinuous pinion, but the space separating two adjacent movable elements being always equal to zero or to a whole number of pitches.

The movable elements are arranged in two groups of side plates which are mounted on the shaft of the device and can have relative angular displacement with respect to each other, said side plates carrying sloped inclines in which are engaged studs rigid with the movable elements. The inclines of one of the groups of side plates has slopes in reverse directions to those of the other group, so that an angular displacement of one of the groups of side plates relatively to the other produces both a radial and angular displacement of each movable element.

Both groups of the incline-carrying side plates can be operatively connected as to rotation when the movable elements are arranged on one of the circles corresponding to a whole number of pitches. These plates can also have relative an-

2

gular displacements for the passage of the movable elements from one position to another.

Other features will appear from the following description in the course of which it will be convenient to call working length, a definite position of the movable elements on a circle of definite diameter, corresponding consequently, to a given speed.

In the accompanying drawing, given by way of example:

Fig. 1 is a sectional half view taken along the line 1—1 in Fig. 2, showing the studs 15 of the movable elements 11 of the present device positioned for the minimum working length, namely sixteen pitches;

Fig. 1A is a sectional half view taken along line 1A—1A in Fig. 2;

Fig. 1B is a sectional view showing the movable elements positioned for a working length of seventeen pitches;

Fig. 1C is a sectional view showing the movable elements positioned for a working length of eighteen pitches;

Fig. 1D is a sectional view of the device, looking from the opposite sides of Figs. 1, 1A, 3 and 3A.

Fig. 2 is a section taken along line 2—2 in Fig. 1;

Fig. 3 is a sectional half view taken along line 3—3 in Fig. 4 showing the studs 15 of the movable elements 11 positioned for the maximum working length;

Fig. 3A is a sectional half view similar to Fig. 1A but showing the movable elements 11 positioned for the maximum working length of twenty-four pitches;

Fig. 4 is a section taken along line 4—4 in Fig. 3;

Figs. 5 to 10 are views showing separately members of the apparatus;

Fig. 5 is a sectional detail view similar to the upper left hand portion of Fig. 2;

Fig. 6 is a detail view of a portion of the control device for initiating changes in the working length;

Fig. 7 is a plan view of a movable element or segment of the sprocket circumference;

Fig. 8 is an elevation of Fig. 7;

Fig. 9 is an elevation of the lug carrier for locking the elements when positioned for the various working lengths, said carrier being mounted on the drive shaft;

Fig. 10 is an edge view of Fig. 9;

Figs. 11 to 13, 13A and 13B are diagrams illustrating the operation of the control device;

Figs. 13C, 13D, and 13E are side, edge and plan

views respectively, of a modified form of movable element or segment;

Figs. 14 to 26 show constructional modifications of various members of the apparatus;

Figs. 14 and 14A are end and elevational views respectively, of a stud which is employed in a slightly modified form of movable element;

Fig. 15 is a side elevation of the movable element for receiving the stud shown in Fig. 14;

Fig. 16 is a view showing the relative position 10 of the plates 4' and 7' for assembling the studs and movable elements thereon;

Fig. 17 is a sectional view through Fig. 16 showing the studs in position;

Figs. 18, 18A and 18B are plan, side and end views respectively, of still another form of movable element;

Fig. 19 is a perspective view of a modified form of inner spool member;

Fig. 20 is a sectional view showing still another 20 modified form of movable element;

Fig. 21 is a sectional view showing a modified form of flanged plate structure for supporting the movable elements;

Fig. 22 is a cross-sectional view showing a form of change speed device for receiving a V-belt instead of a chain;

Fig. 23 is a sectional view similar to Fig. 22, showing a construction with which a cable is adapted to be associated;

Fig. 24 is a sectional view showing a modified form of device, wherein all the movable elements move along radial lines;

Fig. 25 is a view of a slightly modified form of control for initiating relative movement between 35 the slotted plates or spools;

Fig. 26 is a view of still another modified form of control;

Figs. 27 to 39 are diagrammatic views showing several modifications of the operating devices for 40 the change speed mechanisms.

According to the embodiment illustrated in Figs. 1, 1A, 1B, 1C, 1D, 2, 3, 3A and 4, the change speed device for a chain transmission according to the invention is composed of two spool-shaped members 1 and 2 fitting into each other, the member 1 comprising two parallel side plates 3 and 4 fixedly mounted on the shaft 5 of the transmission and member 2 comprising two parallel side plates 6 and 7 rotatably mounted around the hubs of members 2 which in turn are mounted on the shaft 5. These plates are connected together by pins 8. The proximate inner faces of plates 3 and 4 are respectively disposed adjacent the outer faces of plates 6 and 7. In the side plates 3 and 4 of member 1 are cut out slots 9 different from each other but parallel on both side plates, and in the side plates 6 and 7 of member 2 are also cut out slots 10 which will be hereinafter called inclines, the inclines 10 being sloped in reverse direction to the slots 9. Between the side plates 6 and 7 are arranged movable elements 11 (see also Figs. 7 and 8) each comprising two teeth 12 spaced apart to a distance equal to the pitch p of a chain C (Fig. 1D). Said elements 11 are so constructed that, when two of them are in contact, the distance between one tooth of one and the adjacent tooth of the other is equal to the pitch p (Figs. 1A and 1B). Each element 11 has two lateral parallel lugs 13 in contact with the inner proximate faces of the side plates 6 and 7. Each element also has two studs 14 and 15 secured at the ends of element 11 on the lugs 13 at the level of the pitch circle or working length E (Fig. 1A), one of said studs

penetrating an incline 10 and a slot 9 of the side plates 6 and 3, and the other of said studs penetrating the corresponding incline and slot of the side plates 7 and 4.

Figures 1 and 1A illustrate the change speed device when adjusted to a minimum working length E of sixteen pitches p , that is to say, the sprocket has sixteen teeth formed on eight segments or elements 11, each element having two teeth and the elements abutting each other (also see Figs. 1A and 1D). The number of slots 9 and inclines 10 of each of the side plates 3, 4, 6 and 7 is therefore eight.

The maximum working length E^2 is twenty-four pitches (Figs. 3 and 3A) and corresponds to a discontinuous pinion having eight empty spaces each equal to the pitch p , and the space separating the adjacent teeth of two elements spaced from each other being then twice the pitch p . The total number of possible working lengths is nine, namely E , E^1 , through E^8 , each working length differing from the preceding one by a spacing apart of a pair of elements a distance equal to the pitch p , and each slot or incline being formed by a broken line comprising eight straight lines end to end, the intersection of two straight lines corresponding to a given working length. Fig. 1B illustrates the spacing of the elements 11 for a working length E^1 of seventeen pitches, whereas Fig. 1C illustrates the spacing for the succeeding working length E^2 of eighteen pitches. For each succeeding working length, another pair of abutting elements will be spaced apart the distance p to thus enlarge the pitch diameter.

The slots 9 and inclines 10 are traced in such a manner that the points where the slots and inclines cross each other for any given position are always all on one and the same circle and so that the passage from a working length to the next larger working length is effected by spacing apart two adjacent elements 11 a distance equal to pitch p .

At both ends of one and the same diameter of the incline-carrying side plate 7 are provided two bosses 16 and 17, having notches 18 and 19 respectively therein. On the periphery of the slot-carrying side plate 4 are provided notches 20, 20a, 20b, 20c, 20d, 20e, 20f, 20g, and 20h, equal in number to the number of working lengths provided, that is to say, nine in the case chosen.

Against the side plate 4, and loosely mounted on the transmission shaft 5, is arranged a plate 21 (see Figs. 1, 1A, 1D and 9) carrying two lugs 22 and 23. These lugs constantly engage notches 18 and 19 respectively of the side plate 7, and these lugs are also capable of entering the notches 20, 20a, 20b, 20c, 20d, 20e, 20f, 20g, and 20h of side plate 4. The plate 21 will be hereinafter called the lug-carrier. The lug-carrier has a center slot 24 which permits a radial sliding movement of the carrier relative to shaft 5.

The radial movements of the lug carrier 21 are obtained by the engagement of one or the other of the lugs 22 and 23 with a cam 25 (Figs. 1D, 5 and 6). Cam 25 is rockably mounted about a spindle 26 secured by a nut 27 on a small plate 28 which plate is rigid with the main frame of the apparatus. The movements of cam 25 are controlled by a hand-lever 29 connected to said cam through the medium of a flexible Bowden cable 30 attached to a spring 31 secured in its turn at its other end on a tongue 32, said tongue being integral with cam 25. The movement of the tongue 32 is limited by means of two abutments 33 and 34. A spring 35 constantly tends

to urge the tongue 32 against the abutment 33. The spring 31 acts only when the hand-lever 29 is pushed in the direction of the arrow *f*, and it then tends to cause cam 25 to rock about its spindle 26 in the direction of the arrow *F* and to press the tongue 32 against the abutment 34. The spring 35 resists this latter rocking movement and, therefore, when the hand-lever 29 is released, spring 35 tends to cause cam 25 to rock in the direction of the arrow *G* and to press tongue 32 against the abutment 33.

The dimensions, shape and position of cam 25 are such that when tongue 32 is pressed against abutment 33 (Figs. 6 and 1D), the cam is located between the two circles or paths *d*1 and *d*2 followed by the two lugs 22 and 23, the lug following the circle *d*2 of larger diameter passing above the cam 25 without entering in contact therewith (see Fig. 11) and the lug following the circle *d*1 of smaller diameter passing under cam 25 (dead center position). When tongue 32 is pressed against abutment 34 (engagement position), cam 25 is in the dotted line position in Fig. 1D and disposed across the path of the lug following the circle *d*1 of smaller diameter. Then, when the lug-carrier rotates in the direction of the arrow *F*¹ (see Figs. 1D and 12), the pin following the small diameter will be lifted by cam 25, which in turn will lift plate 21. When lug-carrier 21 rotates in the direction of the arrow *G* and on the path *d*2 following the circle of larger diameter, the pin will engage the lower face of cam 25 to thereby lower the plate 21.

The operation of the device is as follows:

Let us assume that the whole of the transmission operates at the minimum working length *E*, that is to say, the working length of sixteen pitches *p*, as illustrated in Figs. 1, 1A, and 1D. In this case, all the movable elements 11 are in contact, forming a continuous pinion and the studs 14 and 15 are located at the ends of the inclines 10 and slots 9 nearest to shaft 5. Lug 22 is engaged in the bottom of notch 18 and also in the bottom of notch 20, thus securing both members 1 and 2 together for rotation with shaft 5 in the direction of the arrow *F*¹, lug 22 following the circle *d*1 of smaller diameter. If it is then desired to pass to a working length *E*¹ of seventeen pitches immediately higher (see Fig. 1B), the hand-lever 29 is actuated in the direction of arrow *f* and cam 25 rocks in the direction of arrow *F* (Figs. 1A and 6).

If the first lug which passes opposite cam 25 is lug 23 which follows the circle *d*2 of larger diameter (Fig. 1D), it passes on the upper half of the cam 25 causing it to rock, spring 31 allowing this movement without having to abandon the hand-lever 29, and nothing takes place. On the contrary, as soon as lug 22 passes opposite cam 25 (Figs. 1D and 13), it abuts against the upper surface of the latter. The lug is then lifted and disengages from notch 20 of disc 4. The lug-carrier 21 is also lifted in its turn the same amount and the opposite lug 23 takes a bearing on the periphery of side plate 4. Lug-carrier 21 is then wedged and stops, which simultaneously causes the stoppage of member 2 constantly connected thereto, member 1 continuing to rotate with shaft 5. As soon as a notch 20a of disc 4 is opposite lug 23, the latter which was firmly pressed against the periphery of disc 4, enters said notch, members 1 and 2 are then again rendered rigid together, lug 22 can continue its movement riding up on cam 25 and pass beyond it, causing it to rock against the action of spring

31. If the hand-lever 29 is abandoned, said cam 25 then comes back under the action of spring 35 to its dead center position, as shown in bold lines in Fig. 1D, after which the pin 23 will follow circle *d*1 and pin 22 follow circle *d*2.

During this operation, the movement of the movable elements was as follows:

As soon as both members 1 and 2 are no longer operatively connected as to rotation and as member 2 is stopped, member 1 continuing to rotate, said members perform a relative angular movement with respect to each other, which will move the elements outward from pitch circle or working length *E* (Fig. 1A) to pitch circle or working length *E*¹ (Fig. 1B). The points where the slots 9 and inclines 10 cross each other are therefore displaced, which points determine the radial positions as well as the circumferential positions of studs 14 and 15. The elements 11 have followed said movement by remaining constantly on one circle for each intermediate position between circles *E* and *E*¹, and the elements also remain in an end-to-end contact, with the exception of two which are spaced from each other (see Fig. 1B). This end-to-end contact is necessary because the circles corresponding to the intermediate positions have increasing diameters and the number and dimension of elements 11 are invariable. Consequently, one of the elements 11 has moved according to a radius, the adjacent element, in the reverse direction to the direction of rotation *F*¹, has been simultaneously subjected to a radial displacement equal to the preceding one and a slight angular displacement in the direction of rotation, the following element to a radial displacement, always constant, and to an angular displacement slightly greater, and so on, up to the last element which has been subjected to the maximum angular displacement.

The notches 20, 20a, 20b, 20c, 20d, 20e, 20f, 20g and 20h are arranged at the periphery of side plate 4 so that the relative movement of members 1 and 2 determining the passage from the position corresponding to the engagement of lug 22 in the notch 20 to the following position corresponding to the engagement of lug 23 in notch 20a determines an angular displacement of element 11 which has moved away from the adjacent one, such that the total movement which has taken place spacing apart these two elements is equal to a pitch *p*.

On the other hand, it will be seen that lug 22 alternates with lug 23 during the successive engagements with notches 20, 20a, 20b, 20c, 20d, 20e, 20f, 20g and 20h, both of said lugs being diametrically opposed. The notches are distributed on two opposite sectors of circles, the notches 20a, 20c, 20e and 20g, corresponding to the odd working lengths of seventeen, nineteen, twenty-one and twenty-three pitches, being arranged on one of the sectors and the notches 20, 20b, 20d, 20f and 20h, corresponding to the even working lengths of sixteen, eighteen, twenty, twenty-two and twenty-four pitches, being arranged on the other sector. If, for example, the cam 25 is held in dotted line position in Fig. 1D while shaft 5 continues to rotate in the direction *F*¹, one of the pins 22 or 23 will successively engage the cam each 180° rotation of the shaft and will be lifted by the cam from a notch at the same time, the other pin will be positioned in the succeeding notch. In this manner, the notches 20, 20a, 20b, 20c, 20d, 20e, 20f, 20g and 20h are successively engaged in the order named by lugs or pins 20 or 23. During the movement of the pins from one

notch to another, the elements 11 are moved to a larger circle, that is to a larger working length. For example, when pin 23 moves into notch $20a$, the elements 11 are positioned on a seventeen pitch diameter circle E^1 (Fig. 1B); when pin 22 engages $20b$, the elements are positioned on an eighteen pitch diameter circle E^2 (Fig. 1C); and so on until the maximum working length of twenty-four pitches is reached (Fig. 3A), at which time the elements are positioned on circle E^8 , and pin 22 will be disposed in notch $20h$.

On the other hand, also it is important that it should not be the same two elements 11 which are spaced from each other for each working length. On the contrary, it is desirable that, at maximum working length (Fig. 3A), each element 11 should be spaced from the adjacent element according to a distance equal to a pitch p . This is easily obtained by tracing the slots 9 and inclines 10 in such a manner that for each change of working length it is a different element which is subjected only to a radial displacement corresponding to a radial element of incline 10 of member 2 . For balancing the various elements in the above mentioned manner, provisions are made so that two successive radial elements of inclines 10 corresponding to two successive changes of working length are located on two opposite sectors of the pitch circle. In other words, two abutting elements will be successively spread apart first on one side of the pitch circle and then on the other at points substantially 180° apart. Inclines 10 and slots 9 are so shaped that the intersection points will position the elements 11 in the above-described positions. Of course, to effect such a result, each element is associated with an incline 10 and slot 9 which differs in shape from the incline and slot of the remaining elements. This is clearly shown in Figs. 1 and 3.

Finally, it is to be noted that, in the case of a transmission having teeth and a sprocket chain of definite pitch, it is indispensable that, at the time the working length is changed, the progressive spacing apart of two movable elements should take place in the part of the sprocket which is not in contact with the chain, as the elements in mesh with the chain cannot obviously move away from each other. This result is obtained by suitably disposing relatively to the inclines 10 , the diameter on which the two notches 18 and 19 are located, the position of said diameter determining the sector in which the elements 11 will be spaced apart (Fig. 1D).

If it is desired to effect the operation reverse to the preceding one, that is to say, to pass from working length of twenty-four pitches to a working length of twenty-three pitches, the following method will be adopted:

Cam 25 having been actuated by means of the hand-lever 29 and being in the position of engagement of Fig. 12, the transmission shaft 5 will be simultaneously given a movement of rotation in the direction of the arrow G^1 , the lug-carrier 21 then rotating in the same direction, the passage of lug 22 following the circle d^1 of small diameter opposite cam 25 will produce no change (Fig. 1D), but as soon as lug 23 following the circle d^2 of large diameter will come in position it abuts against the lower face of cam 25 , which will tend to cause it to lower. When lowering, the pin 23 will press against the periphery of disc 4 and thus cause the opposite lug 22 to come out of the notch $20h$ in which it was engaged. The lug-carrier 21 and member 2 are then held stationary, member 1 continuing to rotate in the direction of the arrow

10

G^1 . Members 1 and 2 then have a relative movement in the reverse direction to that of the preceding case until pin 23 is pressed into notch $20g$. During this relative movement of members 1 and 2 , elements 11 move in the direction for passing from the working length circle E^8 of a given diameter to the working length circle E^7 of smaller diameter corresponding to a working length of twenty-three pitches. The elements 11 which were spaced apart a distance p during the corresponding enlarging step will be returned in contact with each other. As soon as lug or pin 23 enters notch $20g$, the discs will again be rendered rigid together and shaft 5 can re-assume its driving movement in the direction of the arrow F^1 .

In the example described, it has been assumed that the elements 11 have two teeth, it is obvious that said elements might comprise a single tooth. An element of this construction is shown in Fig. 13C and designated by reference character $11a$.

The case of a change speed device having nine speeds has been described, but it is to be understood that the number of speeds depends on the successive supplementary intervals created from the initial position.

For instance, a mechanism of eighteen teeth constituted by single-tooth movable elements will correspond to a pinion having thirty-six teeth when each tooth has been moved one step away from the adjacent teeth on each side thereof. The same mechanism will correspond to a pinion of seventy-two teeth when each tooth has been moved two steps away from its adjacent teeth.

For equivalent intervals, a mechanism having eighteen teeth constituted by movable elements, each having two teeth, will successively correspond to twenty-seven and thirty-six teeth, passing of course through all the intermediate positions. If this same mechanism of eighteen teeth is constructed in groups of three teeth, it will correspond to twenty-four teeth after each element has moved one step away and to thirty teeth when each element has moved two steps away.

Regardless of the number of teeth in each movable element, there are as many speeds as there are possible pitch spacings between the elements plus one. Thus, an 18/36 mechanism has nineteen successive speeds corresponding to the offsetting of one tooth at each change of working speed.

Figs. 14 to 17 illustrate a modified form of a movable element $11b$ in association with plate members $4'$ and $7'$. In this case, one head of a double-headed stud 36 fits in hole 37 formed in the lug 13 of element $11b$ and the other head fits in a hole 38 formed at one of the ends of each slot 9 and incline 10 . When the slots 38 in the slot 9 and incline 10 coincide, a short slot 39 is formed. The assemblage is effected by bringing the studs 36 opposite the various holes and inserting them therein, then by again imparting to both members $4'$ and $7'$ a relative movement so as to restore the studs 36 to the normal starting point.

In the case of mechanisms having only slight torques to transmit, the movable elements can be constructed such as they are illustrated in Fig. 18, that is to say, by doing away with the lateral lugs and by placing the studs 14 and 15 directly in the heel-piece 40 of element $11e$.

Fig. 19 illustrates a constructional modification of an inner member $2a$ which is made in one piece and is provided with flanges 41 and 42 , 75 which in turn are provided with suitable slots 43 .

and 44, allowing the introduction of the movable elements 11c when the latter comprises studs 14 and 15 rigid therewith.

Fig. 20 illustrates a constructional modification of light weight movable elements 11d of small dimensions. The lateral studs of member 11d are formed by sheets of thin resilient steel allowing the elements to be placed in position by pinching them, as shown in the upper portion of this figure.

In Fig. 21 have been shown members 1h and 2h provided with flanges 45 and 46 intended to increase the rigidity thereof. For further increasing said rigidity and at the same time for protecting the structure from dust, the slots 9 of disc 1 can be simply stamped and need not open to the exterior.

Said slots 9, as well as the inclines 10, can be slightly extended at both their ends for collecting and evacuating the foreign bodies which might be introduced in said slots.

In Figs. 22 and 23, methods of construction of movable elements 11e and 11f have been shown where a belt and cable C¹ and C² are employed instead of sprocket chains. In this case, said elements, instead of having teeth, have a smooth groove.

Also, in the case of a smooth belt or cable transmission and when the stresses to be transmitted are small, the slots 9 and inclines 10 can be replaced respectively by simple identical arcs of circles 9a and 10a respectively (Fig. 24). In this case, the eccentricity of the movable elements is uniform during a change of working length, all the elements moving away or approaching each other to the same amount, which can only apply, as indicated above, to the case of a small load since even the elements under the belt must move relatively to each other. In this case, changes of working length as gradual as desired can be obtained by increasing the number of notches 20.

Owing to the dimensions of cam 25, the location of the points where the movable elements move away from each other can be somewhat different accordingly as the change of working length takes place in one direction or in the other. In this case, when the path out of contact with the chain or belt is small (case of an enveloping chain or belt with a returning wheel), it will be advantageous for the cam 25 to be always attacked at the same point, whatever may be the direction of rotation. This result is obtained by means of the device of Fig. 25 in which the cam 25 is replaced by two cams 59 and 61 controlled by a single lever 52 to which they are connected by links 53 and 54, the half-cam 61 being used by lifting in the case the change of working length takes place with a rotation in the direction of the arrow F¹, and the half-cam 59 being used by lowering in the case of change of working length with a rotation in the direction of the arrow G¹.

Fig. 26 illustrates a device for avoiding a change (of the direction of movement before cam 25 is passed). A premature change in direction of movement might effect a locking of the mechanism. For remedying this inconvenience, two fixed cams 55 and 56 are arranged on either side of cam 25 and form with the latter, when it is in position of engagement two channels 57 and 58 in one of which is compulsorily engaged the lug which must determine the operation. These fixed cams have the effect of restoring the lug 22 or 23 to the position it occupied on or under

cam 25 before coming in engagement therewith if the direction of the movement is changed before the lug under consideration has completely passed cam 25.

In all the foregoing, it has been assumed that the change speed device according to the invention was mounted as a driving wheel of the transmission. It is obvious that said device might be applied as such, as a driven wheel, the actuation being then produced by the chain itself instead of being produced by the driving shaft 5 and one of the spool-shaped members, for instance the slotted member 1 being connected to the driven shaft by a free wheel device.

In this case, as member 1 is only connected to shaft 5 when the device rotates in the direction of arrow F¹, it will be possible to effect changes of speed in both directions without having to change the direction of rotation; in fact, it suffices to hold one or the other of members 1 and 2 stationary for the working length to pass to the higher working length or the lower working length.

This result is obtained as diagrammatically illustrated in Figs. 27 to 32 by providing the device with two half-cams 60 and 61 controlled in the same manner as cam 25. The half-cam 60 plays the same part as cam 25 for passing from a given working length to the succeeding longer working length by braking member 2f and the half-cam 61 cooperating with a projection carried by member 1f. The surface of cam 61 which can rock about the spindle 63 is divided into three parts: an incline A—B, a circular part B—C having as axis the general axis of rotation when cam 61 is in position of engagement, and a nose C—D. Let us assume that the device constantly rotates in the direction of arrow F¹, the changes of working length in the direction for passing from a given working length to the succeeding shorter working length take place by stopping member 2f by means of cam 60, as indicated above for cam 25. If it is desired to return from the shorter working length to the longer working length, cam 61 is placed in engagement (Fig. 28). As soon as lug 22 which, for instance, is that which is then engaged in one of the notches 20, 20a, 20b, 20c, 20d, 20e, 20f, 20g and 20h comes in position, it rides up the incline A—B and causes cam 61 to rock about the spindle 63. As soon as the projection 62 comes in position in its turn, it abuts against the end of cam 61 at the moment lug 22 has reached B and is disengaged from the notch 20 in which it was housed (Fig. 29). Member 1f is then stopped and member 2f continues to rotate while lug 22 follows the circular path B—C. During this time, another of the notches 20, 20a, 20b, 20c, 20d, 20e, 20f, 20g and 20h has come in front of the opposite lug 23 which has engaged therein, and lug 22 can then ride up on the incline C—D and pass over cam 61 by causing it to rock in the reverse direction to the preceding one and thus releasing the projection 62 which allows members 1 and 2 operatively connected together by lug 23 to resume their common movement.

In Figs. 33 to 35 have been shown various modifications of the profiles of members 1 and 2 which increase the smoothness of the speed changes.

Although the notches 20 are shown on a straight line, the device when constructed has the notches arranged on a circle. Fig. 33 diagrammatically shows the simplest profile. The incline-carrying member 2g has two diametrically opposed slots 18 and the slotted disc 1g a series of notches 20. The lug 22 passes from one notch 20 to the other com-

11

pletely immobilizing member **2g** at the moment the working length is changed.

In Fig. 34, the general arrangement is the same, but the notches of the slotted member are joined, not by a circular portion as in Fig. 33, but by bosses **64**. Lug **22**, instead of completely stopping the incline-carrying member **2h** at a definite point will have a slight displacement on the cam due to the height of the boss **64** and, instead of the member **2h** being completely held stationary during the change of speed, it will be simply braked relatively to the slotted member. This method allows a smoother change of speed.

In Fig. 35 is shown a device allowing a more important movement of both members **1k** and **2k** during the change of working length and, therefore, a gearing-down allowing greater smoothness. Instead of the incline-carrying member **2k** being provided with only two diametral slots, it can also be divided by notches **65**. The distance between the notches **65** of member **2k** less the distance between the notches **20** of member **1** represents the relative movement necessary for the changes of working length.

When a transmission having wheels of variable diameter is at its minimum working length or at its maximum working length, the engagement of the cam will impart a shock to the mechanism. A device illustrated in Figs. 36 to 39 prevents the cam from coming in engagement even when the control thereof is actuated.

The lug-carrier **21m** is provided with a stud **66** which, in its normal position, at all the intermediate speeds, is not located in the zone of the cam. In Fig. 37 will be seen the mechanism at an intermediate working length. The operation is normal, lug **22** and with it the lug-carrier **21m** is about to be lowered by cam **25m** and the change of length will take place.

In Fig. 38, the mechanism is illustrated at one of the two extreme working lengths and rotating in the direction of the arrow **G'**. The stud **66** has been lifted by a boss **67** carried by a flange **68** rigid with the slotted member **1**. In this new position, stud **66** causes cam **25** to rock (which cam is connected to its control by a spring allowing said movement even when the control lever is maintained in position) at the moment lug **22** comes in position and the latter goes beyond the cam by passing over it.

If the movement takes place in reverse direction (Fig. 39), then it is lug **22** which causes the cam to rock just before the passage of stud **66**, in other words, stud and lug mutually cancel the cam.

For the other extreme working length, it is the other diametral end of the lug-carrier which carries a cancelling stud placed in position at said latter working length by another boss carried by the flange.

The change speed device according to the invention can be applied to all transmissions of the chain, belt or cable type and, in particular, on bicycles, and it is mounted in combination with a chain or belt-tightener of any known type.

The device can also be mounted both on the driving wheel and on the driven wheel, which can allow the chain-tightener to be done away with when the diameters of both wheels vary simultaneously and in reverse direction.

Having now described my invention what I claim as new and desire to secure by Letters Patent is:

1. In a change speed device for flexible transmission means such as a chain, belt or the like,

12

a wheel of variable diameter comprising a plurality of transmission receiving segments supported by said wheel and concentrically positioned about the axis of rotation of the wheel, said segments being in contact with each other when positioned along a circumference of minimum diameter, means individual to each of two adjacent segments for shifting said segments outwardly to a larger concentric circumference and also for spacing the two adjacent segments apart a distance equal to the difference in the lengths of the two circumferences, and means individual to the remaining segments for shifting said segments in contacting position to said other circumference simultaneously with the shifting of said two adjacent segments.

2. In a change speed device for flexible transmission means such as a chain, belt or the like, a wheel of variable diameter comprising two concentric relatively rotatable spool-shaped members, each member having a pair of flanges respectively engaging the flanges of the other member, one of said flanges having a plurality of circumferentially inclined grooves therein and the engaging flange having a plurality of circumferentially and oppositely inclined slots therein, which slots respectively intersect with the inclined grooves, and a plurality of transmission receiving segments supported by said grooves and slots at said intersections whereby relative rotation of said flanges will vary the radial positions of said segments.

3. In a change speed device for flexible transmission means such as a chain, belt or the like, a wheel of variable diameter comprising two concentric relatively rotatable spool-shaped members, each member having a pair of flanges respectively engaging the flanges of the other member, one of said flanges having a plurality of circumferentially inclined grooves therein and the engaging flange having a plurality of circumferentially and oppositely inclined slots therein, which slots respectively intersect with the inclined grooves, a plurality of transmission receiving segments supported by said grooves and slots at said intersections whereby relative rotation of said flanges will vary the radial positions of said segments, a radially movable lock plate constantly engaged with one of said flanges, and means for releasably connecting said plate to said other flange to cause both of said flanges and said plate to rotate together.

4. In a change speed device for flexible transmission means such as a chain, belt or the like, a wheel of variable diameter comprising two concentric relatively rotatable spool-shaped members, each member having a pair of flanges respectively engaging the flanges of the other member, one of said flanges having a plurality of circumferentially and inclined grooves therein and the engaging flange having a plurality of circumferentially and oppositely inclined slots therein, which slots respectively intersect with the inclined grooves, a plurality of transmission receiving segments supported by said grooves and slots at said intersections whereby relative rotation of said flanges will vary the radial positions of said segments, means for rotating one of said members, and means for successively locking and unlocking said flanges at a plurality of relative angular positions while said driving member rotates.

5. In a change speed device for flexible transmission means such as a chain, belt or the like, a wheel of variable diameter comprising a rotat-

able support, a coaxial support rotatable relative to said first support, a plurality of elements equally spaced along a given length of a pitch circle concentric with said axes of rotation, each of said elements being provided with a contact face for receiving said transmission means, means operable by the relative rotation of said supports for radially shifting one of the elements of said given length to a second pitch circle concentric with said axes of rotation, means simultaneously operable by said relative rotation of said supports and individual to each of the remaining elements for shifting the remaining elements of said given length to the second pitch circle while maintaining the initial spacing of the elements throughout said length, means for locking said supports against relative rotation at fixed angular positions, means for releasing said locking means at said positions, and means for automatically operating said locking and releasing means at said positions alternately in succession during the continued rotation of one of said supports.

6. In a change speed device for flexible transmission means such as a chain, belt or the like, a wheel of variable diameter comprising a pair of relatively rotatable disks, a plurality of segments supported by said disks and circumferentially spaced along a circle concentric with the axis of rotation of said disks, each of said segments being provided with a face for receiving said transmission means, means jointly carried by said disks and including a pair of oppositely and circumferentially inclined cam surfaces for shifting one of said segments radially of said axis to a second circle concentric with said first circle, and means jointly carried by said disks and including a second pair of oppositely and circumferentially inclined cam surfaces for simultaneously shifting the adjacent segment radially and circumferentially to said second concentric circle while maintaining a constant spacing from said first segment.

7. In a change speed device for flexible transmission means such as a chain, belt or the like, a wheel of variable diameter comprising a pair of relatively rotatable disks, a plurality of segments supported by said disks and equally spaced a given distance apart along a circular arc concentric with the axis of rotation of said disks, and means operable upon the relative rotation of said disks and individual to each of said segments for simultaneously shifting the latter as initially spaced to another circular arc concentric with said first arc.

8. In a change speed device for flexible transmission means such as a chain, belt or the like, a wheel of variable diameter comprising a plurality of abutting segments supported by said wheel and concentrically positioned about the axis of rotation of the latter, each of said segments being provided with a face for receiving said transmission means, means individual to each of an adjacent pair of said segments for separating the latter segments a distance equal to the difference in the lengths of said respective circumferences upon which the segments are successively positioned and also for shifting the separated segments to another concentric circumference, and means individual to each of the remaining segments for angularly and radially shifting said remaining segments in abutting re-

lationship one with another to said other circumference simultaneously with the shifting of said pair.

9. In a change speed device for flexible transmission means such as a chain, belt or the like, a wheel of variable diameter comprising a plurality of equally spaced segments supported by said wheel and concentrically positioned about the axis of rotation of the wheel, each of said segments being provided with a face for receiving said transmission means, means individual to one of said segments for shifting the latter along a radial line to another concentric circumference, and means individual to each of the remaining segments for respectively shifting the succeeding remaining segments from said first concentric position over progressively increased distances to said other circumference along paths disposed obliquely to radial lines and simultaneously with the shifting of said first segment.
10. In a change speed device for flexible transmission means such as a chain, belt or the like, a wheel of variable diameter comprising a rotatable support, a coaxial support rotatable relative to said first support, a plurality of elements equally spaced along a given length of a pitch circle concentric with said axes of rotation, each of said elements being provided with a contact face for receiving said transmission means, means operable by the relative rotation of said supports for radially shifting one of the elements of said given length to a second pitch circle concentric with said axes of rotation, and means simultaneously operable by said relative rotation of said supports and individual to each of the remaining elements for shifting the remaining elements of said given length to the second pitch circle while maintaining the initial spacing of the elements throughout said length.
11. In a change speed device for flexible transmission means such as a chain, belt or the like, a wheel of variable diameter comprising a pair of relatively rotatable disks, a plurality of segments supported by said disks and equally spaced a given distance apart along a circular arc concentric with the axis of rotation of said disks, means operable upon the relative rotation of said disks and individual to each of said segments for simultaneously shifting the latter as initially spaced to another circular arc concentric with said first arc, and other means individual to each of said segments and operable upon further relative rotation of said disks for separating said spaced segments into two sections by a distance equal to a multiple of said given distance and for simultaneously shifting said segments of the respective sections as initially spaced to a third arc concentric with said second arc.
